DESIGN FOR A LANE MARKER

Raymond H. Osbrink, Los Angeles, Calif.

Application August 12, 1938, Serial No. 79,297

Term of patent 7 years

To all whom it may concern:

Be it known that I, Raymond H. Osbrink, a citizen of the United States and residing at Los Angeles, in the county of Los Angeles and State of California, have invented new, original, and ornamental Design for a Lane Marker, of which the following is a specification, reference being had to the accompanying drawing, forming a part thereof.

In the accompanying drawing—
Fig. 1 is a top plan view of a lane marker showing my new design;

Fig. 2 is a side elevation of the marker; and
Fig. 3 is an end view of the marker.

I claim:

The ornamental design for a lane marker, as shown.

RAYMOND H. OSBRINK.
